CLAIM

The ornamental design for a figurine of a spaniel dog, substantially as shown and described.

DESCRIPTION

FIG. 1 is a front end elevational view of the figurine of a spaniel dog showing our new design;

FIG. 2 is a rear end perspective view of FIG. 1;

FIG. 3 is a side perspective view of FIG. 1;

and

FIG. 5 is a top plan view of FIG. 1.
